UNITED STATES PATENT OFFICE.

FREDERICK WILLIAM LAUER, OF CHICAGO, ILLINOIS.

DESIGN FOR A CHEST.

Application filed March 19, 1926. Serial No. 16,983. Term of patent 3½ years.

To all whom it may concern:

Be it known that I, FREDERICK WILLIAM LAUER, a citizen of the United States, and a resident of the city of Chicago, county of Cook, and State of Illinois, have invented a new, original, and ornamental Design for a Chest, of which the following is a specification, reference being had to the accompanying drawing, forming a part thereof, in which—

Figure 1 is a top plan view of a chest, showing my new design; and

Figure 2 is a front elevational view thereof.

I claim:

The ornamental design for a chest substantially as shown.

FREDERICK WILLIAM LAUER.
